Primary Examiner — Martie K Holtje(74) *Attorney, Agent, or Firm* — Baker & Hostetler LLP(57) **CLAIM**

The ornamental design for a timepiece, as shown and described.

DESCRIPTION

FIG. 1 is a top perspective view of a timepiece according to my new design;

FIG. 2 is a bottom perspective view thereof;

FIG. 3 is a right elevation view thereof;

FIG. 4 is a left elevation view thereof;

FIG. 5 is a rear elevation view thereof, the front elevation view being a mirror image of the rear elevation view;

FIG. 6 is a top view thereof; and,

FIG. 7 is a bottom view thereof.

The broken lines shown are included for the purpose of illustrating portions of the timepiece that form no part of the claim.
